[57] CLAIM

The ornamental design for a motorcycle fuel pump cover, as shown and described.

DESCRIPTION

FIG. 1 is a right side elevational view of a motorcycle fuel pump cover embodying my new design in position of use, it being understood that the broken lines are for illustration purposes only;

FIG. 2 is an enlarged right side elevational view thereof;

FIG. 3 is an enlarged rear elevational view thereof;

FIG. 4 is an enlarged left side elevational view thereof;

FIG. 5 is an enlarged front elevational view thereof;

FIG. 6 is an enlarged top plan view thereof; and

FIG. 7 is an enlarged bottom plan view thereof.
